UNITED STATES PATENT OFFICE.

AARON HAWKINS, OF ROSEBUD CREEK, ALBERTA, CANADA.

AUTOMATIC GATE.

1,289,751.

Specification of Letters Patent.

Patented Dec. 31, 1918.

Application filed July 13, 1918. Serial No. 244,735.

To all whom it may concern:

Be it known that I, AARON HAWKINS, a citizen of the Dominion of Canada, residing at Rosebud Creek, in the Province of Alberta and Dominion of Canada, have invented new and useful Improvements in Automatic Gates, of which the following is a specification.

This invention relates to an automatic gate, and one object is to provide a gate movable in a vertical plane and controlled by a plurality of platform members elevated at their approaching ends at a point adjacent to the lower portion of the gate when the gate is in closed position.

A further object is to provide, in connection with a device of the type indicated, certain novel operating means including a crank shaft controlling a toggle joint structure or the like which in turn controls the position of the approaching ends of the platform members, and controls the position of the gate with reference to the aforesaid ends of the platform members.

25 A still further object is to provide means for operating the crank shaft and the toggle joint structure by a trip or trips when the latter are engaged by the wheel of a wagon moving over the platform.

30 With the foregoing and other objects in view, the invention consists in the novel construction, combination and arrangement of elements hereinafter described and claimed.

35 In the accompanying drawings:

Figure 1 is a view chiefly in top plan.

Fig. 2 is a vertical section.

Fig. 3 is a vertical section from another angle.

40 Fig. 4 is a side elevation.

Fig. 5 is a detail in vertical section and showing in elevation certain structure below the platform.

45 Figs. 6 and 7 are details of construction described below.

The frame on which the platform is mounted is designated 10 and comprises a plurality of longitudinal side bars and end bars or cross pieces, the latter being designated 13 and 14. A central transverse bar or plate member is designated 15 and supports the operating mechanism for the pivotally or hingedly mounted platforms or platform members. These members are designated 16 and 17 and the outer ends thereof are supported in cutaway portions

18 and 19 in cross pieces 13 and 14. Platforms 16 and 17 each carry a hinged member such as 20, the oppositely located hinged members of the respective pairs being adjacent each other and being retained by a transverse bar 22. The operation of this bar, that is the shifting of the bar to control its upper and lower positions, effects the control of the platform members and the control of the gate.

50 Bar 22 passes through slots 23 in the lower ends of the uprights 24 and 25 constituting the gate frame. Bar 22 is engaged by a member 25 of the toggle joint 70 connection 26, the other arm of the toggle joint being designated 27. Arm 25 is provided with an aperture 28 through which bar 22 loosely passes.

The toggle joint is controlled by means 75 of a transverse pin 30 operated by crank shafts 31 arranged in alinement and extending transversely across the frame 10. Each crank shaft is mounted to rotate in bearings 32 suitably supported.

80 Connected with each crank shaft is an operating rod 33 or 34, as the case may be, the rods extending outwardly and longitudinally of the frame 10 and each of these rods being operated by a trip such as 35, 85 these trips being pivotally mounted at the outer ends of the platform members 16 and 17.

85 When the gate is closed the central portions of the platform members are elevated, 90 and the toggle joint is in a position with its arms extended. The operation of either trip 35 by contact due to the passage of a wagon wheel over the platform, partly rotates the crank shaft connected therewith 95 and collapses the toggle joint causing transverse bar 22 to fall and permitting the adjacent ends of the platform members 16 and 17 to drop to a horizontal position.

95 The gate frame including uprights 24 and 100 25 is connected at its upper portion by means of transverse members 40, and the gate 41 operates between the uprights 24 and 25, the latter being provided with guides 43 and 44 engaged by wheels or rollers 45 mounted 105 on the gate.

Near the lower portion of the gate I connect the lazy-tongs 47 for controlling the gate. The upper elements of the lazy-tongs are connected by means of a pivot 48, and 110 at the point where said upper elements are pivotally connected with the adjacent ele-

ments of the lazy-tong structure, I also connect operating arms 50 and 51, the latter being pivotally connected at their outer ends with levers 52 and 53 pivotally mounted on the uprights 24 and 25.

Levers 52 and 53 may be provided with a series of notches 54 and may also be provided with a series of apertures 55, permitting of the adjustment of the flexible connecting members 57 thus permitting their location at a suitable point, and also permitting of the adjustment of the pivotal mounting of the levers 52 and 53. Connecting members 57 are controlled by means of the transverse bar 22, for the purpose of operating the gate when said bar 22 is operated and carried downwardly by the collapse of the toggle joint. This downward movement of the bar 22 produces a corresponding downward movement of the outer ends of levers 52 and 53 and raises the gate in view of the lazy-tong connection above specified.

The connecting members 57 may include turn-buckles or other adjusting devices.

The weight of the gate is to be sufficient to overbalance the platform members and effect the automatic closing of the gate. If desired the gate can be adjusted so that when in an approximately closed position, it will still leave sufficient space for small animals to pass through the gate opening.

What is claimed is:

1. In a device of the class described, a main frame, a plurality of pivotally mounted platform members, the ends of which approach each other, a transverse bar constituting a part of said pivotal mounting, a toggle joint controlling the bar, a crank shaft controlling the operation of the toggle joint, a trip mounted on the platform and controlling the crank shaft, a gate frame extending vertically from the main frame, a slidable gate therein, a plurality of levers mounted on the gate frame and having their inner ends spaced apart, a lazy-tong structure connected with the spaced ends of the levers and with the gate, and means con-

nnecting the outer ends of the levers with the transverse bar controlled by the toggle joint. 50

2. In a device of the class described, a main frame including a transverse bar mounted at the central portion thereof, a crank shaft mounted on said bar, a toggle joint controlled by the crank shaft, a bar extending across the main frame and pivotally connected with one arm of the toggle joint, said last named bar being controlled by the toggle joint and effecting movement of the bar in a substantially vertical plane, platform members carried by the main frame and approaching each other at a point adjacent to the bar operated by the toggle joint and hingedly connected with said bar, a trip for operating the crank shaft, a gate mounted for vertical movement above the platform, a lazy-tong structure, connected with the gate, a lever connected with the upper portion of the lazy-tong structure and an adjustable device connecting the lever with the transverse bar operated by the toggle joint. 60

3. In a device of the class described, a main frame, a vertical frame, guides carried by the members of the vertical frame, 75 a gate slidably mounted in the guides, a lazy-tong structure, connected with the gate at the lower portion thereof, means for pivotally connecting the upper portion of the lazy-tong structure with the gate frame, 80 a plurality of pivotally mounted levers controlling the lazy-tong structure and the vertical position of the gate, a plurality of platform members normally elevated at their approaching ends along a line below 85 the gate, the approaching ends of the platform members being elevated when the gate is in its lower position, and means controlled by the platform members for raising the gate. 90

In testimony whereof I affix my signature in presence of a witness.

AARON HAWKINS.

Witness:

J. B. SMITH.
